Primary Examiner — Karen S Acker(74) Attorney, Agent, or Firm — Covington & Burling LLP; Andrea G. Reister, Esq.; Melody Wu, Esq.(57) CLAIM

The ornamental design for packaging for a beverage container, as shown and described.

DESCRIPTION

FIG. 1 is a perspective view of packaging for a beverage container showing the new design;

FIG. 2 is a front view thereof;

FIG. 3 is a top view thereof;

FIG. 4 is a right side view thereof;

FIG. 5 is a left side view thereof;

FIG. 6 is a rear view thereof; and,

FIG. 7 is a bottom view thereof.

The broken lines in the drawings represent unclaimed environmental subject matter.
